UNITED STATES PATENT OFFICE.

JOHN EDWARD OGDEN, OF MOUNTAINVILLE, NEW YORK.

SECTIONAL DOOR.

Application filed August 12, 1921. Serial No. 491,696.

To all whom it may concern:

Be it known that I, JOHN EDWARD OGDEN, a citizen of the United States, and a resident of Mountainville, town of Cornwall, 5 county of Orange, and State of New York, have invented certain new and useful Improvements in Sectional Doors, of which the following is a specification.

This invention relates to doors and more 10 particularly to sectional doors of the type used in pier sheds, warehouses and like structures.

Doors of the character described are usually very large and due to their exposed location are subjected to severe stresses and pressures. For instance, the wind pressure against such doors has been found to be so severe as to force the upper section inwardly to such an extent that the bottom of this 20 section would be forced out of cooperation with the interengaging parts of the lower door section.

This invention has for its object to overcome the difficulties above noted and to prevent such separation of the door sections. 25

Another object of the invention is to provide means in connection with sectional doors for securing the sections in engagement with each other and with the wall or 30 posts upon which they are mounted.

Another object of the invention is to provide means in connection with sectional doors for centering the door, thereby equalizing the laps at the edges thereof and 35 bringing the locks into correct alignment.

Further objects of the invention will appear as the description proceeds.

The objects of the invention are attained in the embodiments illustrated by means 40 such as a wedge for forcing the door or sections thereof against the door casing or posts and further by providing means for forcing the sections upon their closing into close engagement with each other. Means is 45 also provided on the casing and door for centering the door sections with respect to the casing.

Referring to the drawings,

Fig. 1 is an elevational view illustrating 50 portions of the upper and lower door sections, of the door casing or post and of the locking or securing means.

Fig. 2 is an end view of the construction

shown in Fig. 1 taken substantially on line 2-2 of Fig. 3. 55

Fig. 3 is a horizontal sectional view taken substantially on line 3-3 of Fig. 1.

Fig. 4 is an elevational view similar to Fig. 1 but showing another form of the invention. 60

Fig. 5 is an end elevation of the construction shown in Fig. 4 taken substantially on line 5-5 of Fig. 6.

Fig. 6 is a horizontal sectional view taken substantially on line 6-6 of Fig. 4. 65

Fig. 7 is an elevational view of another form of the invention showing means for centering a door section and for moving the section against the door casing or post.

Fig. 8 is a sectional elevation of the construction shown in Fig. 7 taken at right angles to Fig. 7. 70

Fig. 9 is an elevational view, partly broken away and partly in section, showing another form of means for centering and 75 moving the section against the casing.

Fig. 10 is a sectional elevation taken at right angles to Fig. 9.

Fig. 11 is an elevational view of another means for locking the door section against 80 the casing and

Fig. 12 is a sectional elevation of the construction shown in Fig. 11 taken at right angles to Fig. 11.

In the drawings I have shown a door 85 comprising a lower section 10 and an upper section 11, the section 10 having a laterally extending flange 12 mounted between flanges 13 carried by the upper section. One side wall of the door casing or one of the door 90 posts is shown at 14, the post being recessed for the reception of the door.

In order to lock the door sections against separation and to retain them in position against the door casing or post a U-shaped 95 bracket 15 is secured to the lower portion or adjacent the lower edge of the upper door section 11.

The bracket 15 has an inclined or wedge shaped portion 16 extending laterally and 100 adapted to be engaged by a bracket 17 carried by the top of the lower door section. The bracket 15 also has a laterally extending portion 18 having an inclined edge 19 adapted to engage a wedge 20 carried by 105 bracket 21 secured to the post or casing 14

adjacent the lower end of the top section 11.

The construction shown in Figs. 1-3 inclusive operates as follows. When the upper section 11 reaches its closed position, 5 shown in full lines in the drawings, the portion 18 of the bracket 16 will engage the wedge 20 carried by the post and this section will thereby be forced inwardly into firm engagement with the portion 22 of the 10 post 14. As the lower section reaches its lower limit of movement, the bracket 17 will engage the wedge 16 and the section 10 will be drawn into firm engagement with the casing 14 as shown at 14'. It will thus 15 be seen that the upper door section will be retained firmly against the door casing or post and that the lower door section will be firmly locked against separation from the upper section and into tight engagement 20 therewith. The engagement between bracket 17 and portion 16 also prevents the bottom of the upper section 11 from rising and freeing itself from the lower section, under wind pressure which tends to separate the 25 sections.

It will be understood, of course, that locking and retaining means can be and preferably is provided for both sides of the door.

Referring now to the form of the invention shown in Figs. 4, 5 and 6, the door sections 10 and 11, respectively, are mounted in a manner similar to that already described. In this case, however, the upper section 11 has secured thereto a laterally extending bracket 30 which is adapted to be engaged by a bracket 31 carried by the lower section 10 when the latter reaches its lower limit of movement. The post 14 in this instance has secured thereto a laterally extending bar or strip 32 and the lower section 10 has secured thereto adjacent its upper end a wedge 33 which is adapted to engage the strip 32 and retain the door sections against lateral movement and press the section 10 into engagement with the post 14.

The construction just described operates as follows. Assuming that the upper section 11 is in the full line position shown, the lower section will be limited in its downward movement by the floor and at its lower limit the bracket 31 engages the bracket 30. This will prevent separation of the doors by any external pressure. As the door section 10 reaches its closed position the engagement of the wedge 33 with the bar 32 will force the section 10 into firm and tight engagement with the posts or door casing.

In order that the locking means, such as are shown for instance in Figs. 1-3, may be effective and operate efficiently, it is desirable that the door sections be centered with respect to the opening in the wall or with respect to the door casing.

In Figs. 7 and 8 means is shown for centering one of the sections of the door and

it will be understood that this section may be one of the upper sections or the lower section. In illustrating the device the upper section 11 is shown as having a downwardly extending member or bracket 40. The member 40 has one edge beveled or inclined as shown at 41 and has one surface beveled or inclined as shown at 42. The door casing or post 14 has secured thereto a bracket 43 having a part 44 adapted to be engaged by the edge 41 of the bracket 40 and the bracket 44 also has a beveled part 45 over which the beveled end 42 of the bracket 40 may ride as the section 11 moves to its lower limit of movement. When the section 11 has moved to this position an edge 46 of the bracket 40 engages an edge 47 of the bracket 43 thereby centering the section 11 with respect to the door casing and equalizing the lap on each edge of the door thus bringing the locks into correct alignment. The engagement of the edges 41 and 44 moreover presses the door section 11 into tight engagement with the door casing.

In Figs. 9 and 10 another form of means for accomplishing this same object is illustrated. In this form a bracket 50 is secured to the casing or post 14 and this bracket has a beveled edge 51 and a beveled surface 52. The edge 51 is adapted to engage an inclined edge 53 of a channel iron 54 carried by the bottom of the section 11. The edge 52 is adapted to engage a beveled surface 55 of an angle iron insert 56 carried by the bottom of the section 11. Thus by the engagement of the surfaces 51 and 53 the section 11 is moved into tight engagement with the door casing and by the engagement of surfaces 52 and 55 the door section 11 will be centered.

In Figs. 11 and 12 another form of means is shown for moving the section 11 into engagement with the door casing. In this embodiment an overhanging bracket 60 is carried by the section 11 and this bracket engages a bracket 61 carried by the door casing or post 14. These brackets have beveled edges adapted to coact in moving the section 11 against the door casing when this section reaches its lower limit of movement.

Although the brackets shown in Figs. 7-12 inclusive have been particularly illustrated in connection with the upper door section it should be understood that they are equally well adapted for use in connection with any of the other door sections or if desired with a door having a single door section.

Although certain specific embodiments of my invention have been particularly illustrated and described, it will be understood that the invention is capable of modification and that changes in the construction and in the arrangement of the various cooperating parts may be made without departing from

the spirit or scope of the invention as expressed in the following claims.

What I claim is:

1. In combination, a door post, vertically movable door sections and means carried by the post for moving one of the sections into engagement with said post and means carried by the said section for moving another section into engagement with the post. 60
2. In combination, a door post, vertically movable door sections and wedging means carried by the post for moving one of the sections into engagement with said post and wedging means carried by the said section for moving an other section into engagement with the post. 65
3. In combination, a door post, a pair of vertically movable door sections, a member carried by one section, and a wedge carried by the other section and engageable by said member to draw the sections together. 70
4. In combination, a door post, a pair of vertically movable door sections, a member carried by one section, a wedge carried by the other section and engageable by said member to draw the sections together, and means for moving the upper section into engagement with said post. 75
5. In combination, a post, a pair of vertically movable door sections, a laterally extending member carried by one section, a wedge carried by the other section engageable with said member and means carried by the post for moving the upper section into tight engagement with said post. 80
6. In combination, a post, a pair of vertically movable door sections, a laterally extending member carried by the lower section, a wedge carried by the upper section engageable with said member and means carried by the post for moving the upper section into tight engagement with said post. 85
7. In combination, a post, a pair of vertically movable door sections, a member extending laterally from one door section, a member carried by said post and means carried by the other section engageable with the laterally extending member and with the member carried by the post to lock said sections together and to move the sections toward the post. 90
8. In combination, a post, a pair of vertically movable door sections, a member extending laterally from one door section, a wedge member carried by said post and means carried by the other section engageable with the laterally extending member 100
9. In combination, a post, a pair of vertically movable door sections, a member extending laterally from the lower door section, a wedge member carried by said post and means carried by the upper section engageable with the laterally extending member and with the member carried by the post to lock said sections together and to move the sections toward the post. 105
10. In combination, a post, a pair of vertically movable door sections, a member extending laterally from one door section, a wedge member carried by said post and a U-shaped member carried by the other section engageable with the laterally extending member and with the member carried by the post to lock said sections together and to move the sections toward the post. 110
11. In combination, a post, a pair of overlapping vertically movable door sections, means carried by the upper section for preventing separation of the sections, a member secured to said post and means carried by the lower section and engageable with said member for moving said sections into close engagement with said post. 115
12. In combination, a post, a pair of overlapping, vertically movable door sections, means carried by the upper section for preventing separation of the sections, a laterally extending member secured to said post and wedge means carried by the lower section and engageable with said member for moving said sections into close engagement with said post. 120
13. In combination, a door casing, a vertically movable door section and means including cooperating wedge members carried by the casing and section for moving said section against the casing and for centering the section with respect to the casing. 125
14. In combination, a door casing, a vertically movable door section, a double wedge member carried by the casing and a double wedge member carried by the section and engageable with the first member for moving the section against the casing and for centering the section with respect to the casing. 130

In witness whereof, I have hereunto set my hand this 19th day of July, 1921.

JOHN EDWARD OGDEN.

Witness:

I. B. MOORE.
